UNITED STATES PATENT OFFICE

161,033

COMBINATION RING AND CIGARETTE HOLDER

Sam Marcus, Newark, N. J.

Application November 14, 1949, Serial No. 6,033

Term of patent 3½ years

(Cl. D85—8)

To all whom it may concern:

Be it known that I, Sam Marcus, a citizen of the United States, residing in the city of Newark, county of Essex, and State of New Jersey, have invented a new, original, and ornamental Design for a Combination Ring and Cigarette Holder, of which the following is a specification, reference being had to the accompanying drawing, forming a part thereof:

I claim:

The ornamental design for a combination ring and cigarette holder substantially as shown.

SAM MARCUS.
